UNITED STATES PATENT OFFICE.

JOHN ISAAC THORNYCROFT, OF BEMBRIDGE, ISLE OF WIGHT, ENGLAND.

HOLDING MEANS FOR DOORS AND THE LIKE.

Application filed November 23, 1921. Serial No. 517,243.

To all whom it may concern:

Be it known that I, JOHN ISAAC THORNYCROFT, a subject of the King of Great Britain and Ireland, residing at Bembridge, Isle of Wight, England, have invented Improvements in or Relating to Holding Means for Doors and the like, of which the following is a specification.

This invention has reference to door holding devices of the kind comprising a piece of springy sheet metal bent upon itself to form two overlapping laterally displaced portions one of which, hereinafter referred to as the stationary portion, is adapted to be fixed against the side of a door frame opposite which the free edge of a door will be located when the door is closed, and the other of which forms a resilient blade or striking plate, against which the free edge 20 of the door will bear during the closing of the door and when the door is closed.

In such door holding devices as heretofore proposed, the resilient striking plate portion has not been made of greater length than the stationary overlapping portion of the device and each such device has been so fixed to a door frame that the door when being closed will first act upon the end portion of the resilient striking plate that is connected to the stationary plate, that is to say, at the part thereof that will require the greatest force to be applied to it by the door, to displace it in order that the door may be closed.

The present invention has for its object to provide a door holding device of the kind referred to adapted to be fixed to the side of a door frame as before but so constructed that when the door with which it is to be used is being closed, the edge of the door will first engage the free end portion of the resilient striking plate so that the door will need to exert at first, only a small pressure against the said plate gradually to displace or deform it about its fixed inner end portion, the pressure between the blade or plate and door gradually increasing as the door is closed.

For this purpose in a door holding device 60 of the kind referred to constructed according to the present invention, the resilient striking plate is provided with a free end

portion that overhangs or extends beyond and is inclined towards the plane of the stationary portion of the device. The construction is such that when the holding device is fixed to a door frame in the position hereinbefore described and the door associated therewith is being closed, the free vertical edge of the door will first come into contact 60 with and slide along the bent overhanging free end portion of the resilient striking plate and gradually and gently displace such plate towards the stationary portion of the holding device and will hold the plate 65 in the deformed condition when it is completely closed, the said resilient striking plate, by reason of the pressure between it and the edge of the door, acting to hold the door firmly in the closed position and prevent it rattling whilst permitting the door 70 to be easily opened by pressure sufficient to overcome the friction between it and the striking plate.

By the construction described, it will be understood that the distance between the bent end portion of the resilient striking plate, where it is connected to the stationary portion of the holding device, and the point 80 at which the pressure of the door is being applied to such striking plate, gradually decrease as the door is being closed, whilst the pressure acting to hold the door closed will gradually increase, which is an important advantage.

In the accompanying illustrative drawings, Fig. 1 shows in perspective, one construction of door holding device according to the invention. Fig. 2 shows part of a door frame and door with a holding device 90 such as shown in Fig. 1 fixed to the door frame, the door, which is designed to be opened in one direction only, being shown in full lines in its closed position and in dotted lines in its partly open position. Fig. 95 3 is a horizontal section, similar to Fig. 2, showing the holding device associated with a door frame and a door designed to be opened in each direction.

According to the example shown, the 100 holding device consists of a strip of spring metal, for instance steel or bronze of uniform width, bent upon itself so as to form two laterally displaced side portions α and

b connected together by an intermediate loop portion *c*. One end portion of the device, namely *a*, is adapted, as by the provision of one or more holes *d* therein, one hole only is shown in the example, to be readily secured, as by one or more screws *e*, one screw only is shown, to the side of a door frame *f* in known manner. The other portion *b*, which forms the resilient striking plate, is bent to a convex shape, as shown, and is, according to the present invention, made of greater length than the stationary portion *a* and bent so that its free end portion *b*¹ overhangs or extends beyond and is inclined towards the plane of the stationary portion *a*. As will be seen, when such a fastening device is fixed to the door frame *f* in position for use, as is shown in Fig. 2, and the associated door *g* is being closed, the latter will first act against the free end portion *b*¹ of the resilient striking plate *b* so as gradually to force such plate towards the stationary portion *a* and hold it in the compressed or strained condition, as shown in full lines in Fig. 2, so long as the door remains in the closed position. When the door is being closed, the distance between the bent loop end *c* of the device and the point on the resilient striking plate *b* against which the edge of the door acts, is gradually decreased, whilst the reaction between the said compressed and strained striking plate *b* and the edge of the door *g* gradually increases and is finally such as will effectually hold the door in the closed position and prevent it rattling whilst enabling it to be opened with very little effort. When the door is opened sufficiently to release the striking plate, as shown in dotted lines in Fig. 2, the said plate will resume its normal position, also shown in dotted lines in Fig. 2. The stationary portion *a* of the holding device, which may be flat as shown, may be located in a recess *h* in the door frame *f*. The free edge of the bent end portion *b* may, as shown, be bent to form a rounded or bended edge *b*².

To admit of the screw *e* being easily fixed in place, the free end portion *b* of the holding device is formed with a hole *d*¹ opposite the hole *d* in the fixed portion *a* of the device.

The portions *a* and *b* of the device are preferably made from a wide piece of strip metal of uniform width so that the portion *b* constituting the striking plate shall afford, as shown, a wide bearing surface for contact with the door.

A door holding device of the kind described can be used with a door or the like designed to open in one direction only, as shown in Fig. 2, where the door *g* closes against the end wall *h*¹ of the recess *h*, but it may be used with a door arranged to

open in opposite directions, as shown in Fig. 3, the door frame *f* in this case being adapted to admit of the door *g* being moved past it in each direction. In this case, the advantage resulting from providing the resilient striking plate *b* with a bent end portion *b*¹ as described is only obtained when the door swings in one direction.

What I claim is:-

1. A door holding device comprising a strip of springy material bent upon itself and forming two adjacent laterally displaced side portions connected together by an intermediate loop portion, one of the side portions being flat throughout its length and adapted to be fixed to the side of a door frame and the other portion, which is adapted to form a striking plate, is of greater width than the said flat portion and consists of two integral parts one of which adjacent to the loop portion, is flat and the other of which, extends beyond the free edge of the first mentioned portion and is bent laterally in the direction of and so as to overlap the free edge of the first mentioned side portion and also the edge of a door to which such side portion is attached, substantially as described.

2. A door holding device comprising a strip of springy material bent upon itself and forming two adjacent laterally displaced side portions of unequal length connected together by an off-set loop portion, the one side portion of smaller length being flat and adapted to be fixed to the side of a door frame and the other or longer side portion being flat at the part thereof opposite the first mentioned flat side portion whilst the remaining part is externally of convex shape and extends outward to a considerable distance beyond and is bent in a direction towards and so as to overlap the free edge of the first mentioned flat side portion and form a resilient striking plate, substantially as described.

3. A door holding device comprising a wide strip of springy material of uniform width bent upon itself to form two adjacent laterally displaced side portions of equal width connected together by an offset loop portion, one side portion being flat and adapted to be fixed to one side of a door frame and the other side portion being free and bent to a convex shape externally and having its outer free curved end portion extending beyond, towards and overlapping the free edge of said flat portion, substantially as described.

4. The combination with a door frame having a recessed side, and a swing door, of a holding device comprising a strip of springy material bent upon itself and forming two adjacent laterally displaced side portions connected together by a lateral off-set loop portion, one side portion being flat

and secured to one side of the door frame with the off-set portion located in the recess in the door frame and the other side portion being normally of convex shape externally and of greater length than the flat portion and having a convex free end portion extending beyond, towards and over-

lapping the free edge of the fixed side portion of the device and arranged in the path of the edge of the swing door, substantially as described for the purpose set forth. 10

Signed at Bembridge Isle of Wight England this first day of November 1921.

JOHN ISAAC THORNYCROFT.
